DESIGN FOR A SLIDE FASTENER

Warren D. Blatz, Bridgeport, Conn.

Application July 12, 1935, Serial No. 57,605

Term of patent 14 years

To all whom it may concern:

Be it known that I, Warren D. Blatz, a citizen of the United States, residing at Bridgeport, in the county of Fairfield and State of Connecticut, have invented a new, original, and ornamental Design for Slide Fasteners, of which the following is a specification, reference being had to the accompanying drawing, forming a part thereof.

In the drawing:

Fig. 1 is a plan view of a slide fastener showing my new design;

Fig. 2 is a sectional view on line 2—2 of Fig. 1.
I claim:

The ornamental design for a slide fastener, as shown.

In testimony whereof I affix my signature.

WARREN D. BLATZ.
